(57) **CLAIM**

The ornamental design for a “pen,” as shown and described.

DESCRIPTION

FIG. 1 is a perspective view of a pen showing a new design; FIG. 2 is a front view thereof;

FIG. 3 is a back view thereof;

FIG. 4 is a left view thereof;

FIG. 5 is a right view thereof;

FIG. 6 is a bottom view thereof;

FIG. 7 is a top view thereof; and,

FIG. 8 is a perspective view of a pen showing a new design. The subject matter shown in broken lines is included to show portions of the pen that form no part of the claimed design.
